UNITED STATES PATENT OFFICE.

MARIANO LA BARBERA, OF NEW YORK, N. Y.

STOVE.

Application filed October 11, 1923. Serial No. 667,937.

To all whom it may concern:

Be it known that I, MARIANO LA BARBERA, a citizen of the United States, residing at New York, in the county of New York and 5 State of New York, have invented certain new and useful Improvements in Stoves, of which the following is a specification.

This invention relates generally to stoves, being intended more particularly for embodiment in cooking stoves, the invention having for a main object to economize fuel by causing the heated gases of combustion to be conducted directly to the points where the heat is desired, that is under the openings in the stove top which receive the cooking vessels.

A further object is to provide an opening through which fresh fuel may be thrown on the fire independently of the said openings, and without the need of disturbing such cooking vessels as may be on the stove.

A still further object is the provision of means permitting the broiling of meat in the fire chamber, while maintaining the latter closed, so that volatile matters resulting during the process will be conducted through the chimney, and odors will not permeate the kitchen.

For further comprehension of the invention, and of the objects and advantages thereof, reference will be had to the following description and accompanying drawing, and to the appended claims in which the various novel features of the invention 35 are more particularly set forth.

Fig. 1 of the drawings is a front view showing my improved stove.

Fig. 2 is an end view.

Fig. 3 is a top plan view.

40 Fig. 4 is a plan view of a gridiron adapted to be inserted in the fire chamber of the stove when broiling meat.

Fig. 5 is a detail elevational view showing the conduit dampers.

45 Fig. 6 is a cross sectional view through the central conduit.

Fig. 7 is a fragmentary end view showing a modification.

As here embodied my improved stove comprises a base 10 which supports a casing 11, the back and sides of the casing being substantially unbroken, while the front of the casing is provided with a number of doors which give access to the interior thereof, the interior of the casing being divided by suitable partitions to form a pair of

ovens at either side between which is the fire chamber and ash pit. The doors which lead into the oven are indicated at 12 in Fig. 1, while the main fire door is numbered 13 and the ash pit door 14, a small door 15 being provided at a suitable distance above the fire grate through which fresh fuel may be thrown on the fire.

The top of the stove is indicated at 18 and is spaced a short distance above the top of the fire chamber proper, a shallow dome 19 extending across the top of the said fire chamber. The top of the stove is here shown as provided with three openings to receive cooking vessels, consisting of central and side openings which are closed by the usual removable covers or lids 21. From the dome 19 of the fire chamber three conduits, consisting of a central conduit 25 extending directly upward, and the side conduits 26 which are inclined upward away from one another, lead to the openings in the stove top, thereby serving to conduct the hot gases of combustion directly under these openings, and confining the heat given off by the fuel to the parts of the stove top where it is to be utilized. From the upper portions of these conduits 25 and 26 other conduits 27 and 28 respectively lead rearwardly to the usual chimney connection 29, which latter is here shown with a small door 30 therein. The space in the stove surrounding the said conduits may be filled with asbestos.

In connection with my improved stove I provide means whereby meat may be broiled in the fire chamber and to this end a narrow opening closed by a door 15' is formed in the door 15 through which a gridiron 95 16 such as shown in Fig. 4 containing the meat to be broiled may be inserted into the fire chamber. I have shown in Fig. 1 a water tank 32 connected by pipes 33 with a heater coil in the stove which may have 100 connections leading to opposite ends of the stove so that the tank may be placed at either end of the stove as desired.

In order to obviate chance of injury to the person using the stove, that is placing or removing vessels thereon, or in placing material in such vessels or removing material therefrom, I have provided on the front of the stove a cage-like projection 35 composed of suitable wires or bars and which is 110 fixed to the front of the stove and projects forwardly therefrom as shown. In Figs. 1

and 2 of the drawing I have shown the stove as provided with a hinged leaf 36 which is normally erected to vertical position, but which may be swung down upon the top of 5 the stove when desired.

I may also provide means for controlling the conduits 27 and 28 this means being preferably arranged so that the conduits 28 are controlled as a unit, and separately 10 from the central conduit 27. As here shown dampers in the form of disks 40 and 41 are provided in the respective conduits 27 and 28, these dampers being all mounted on a common rod 42 which extends from end to 15 end of the stove and is supported in the end walls of the casing 10, one end of this rod projecting from the said casing and having a head 43 thereon for turning purposes. The dampers 41 are fixed to the rod and 20 the damper 40 is provided with a hub 40 through which the rod 42 passes freely, this hub element being formed with an arcuate slot 44 into which projects a pin 25 45 on the rod 42. This slot 44 extends through an arc of ninety degrees and the parts are so arranged that when the damper 40 is horizontal that is opening the conduit 27, the dampers 41 are vertical that is in 30 position with the conduits 28 closed, the pin 45 is at one end of the arcuate slot 44. A weight 47 may be attached to the damper 40 to normally hold it in horizontal position, a stop lug 48 being indicated on the 35 conduit against which the damper rests at its lower edge when open, while a second stop lug 49 may be formed in the conduit against which the damper bears when closed. It will be obvious that, with the 40 parts arranged as above set forth, when the rod 42 is turned in a direction to swing the pin 45 toward the right, considering the parts as shown in Fig. 6, the damper 40 will be closed and the dampers 41 opened, while if the rod be swung in an opposite 45 direction the dampers 41 will be opened while the central damper 40 will not be moved and the passage will be opened through all three conduits. A suitable spring pressed latch 52 may be mounted 50 on the head 43 of rod 42 and engage a notched collar 53 on the casing 10 to hold the rod in adjusted positions.

In Fig. 7 I have indicated the top of the stove as provided with an upstanding flange 18^a extending along the back thereof, and to the top edge of this flange 18^a is pivoted as at 56 an open-front casing 57 having a number of shelves 58 therein to receive small articles which it may be 55 desired to keep warm. This casing is retained in erect position by means of a number of leaves such as 59 pivoted to the flange and adapted to be swung into suitable recesses in the flange 18^a to permit of the casing being swung down to rest upon the stove 60 65

top, as indicated in broken lines, thereby providing a support or shelf on which vessels may be placed which require to be kept warm.

Having thus described my invention what 70 I claim as new and desire to protect by Letters Patent of the United States is as follows:

1. A stove having a fire chamber, a dome 75 extending across the top of said fire chamber, a stove top spaced a distance above said dome and having a central and two side openings for the reception of vessels, individual conduits leading from the said dome to the respective openings, and dampers in the respective conduits, and a common operating rod on which all of said dampers are mounted, the dampers in the side conduits being fixed on said rod, and the damper in the central conduit being 80 movable on said rod to permit said side dampers to operate in unison independently of the damper in the central conduit. 85

2. A stove having a fire chamber, a dome 90 extending across the top of said fire chamber, a stove top spaced a distance above said dome and having a central and two side openings for the reception of vessels, dampers in the respective conduits, a rod extending transversely through all the conduits 95 and having the dampers in the side conduits fixed thereon, and means providing a lost motion connection between said rod and the damper in the central conduit. 100

3. A stove having a fire chamber, a dome 105 extending across the top of said fire chamber, a stove top spaced a distance above said dome and having a central and two side openings for the reception of vessels, dampers in the respective conduits, a rod extending transversely through all the conduits and having the dampers in the side conduits fixed thereon, and means providing a lost motion connection between said rod and the damper in the central conduit, said 110 means comprising a pin on the rod engaging in an arcuate slot in a hub element of the damper through which the rod passes freely. 115

4. A stove having a fire chamber, a dome 120 extending across the top of said fire chamber, a stove top spaced a distance above said dome and having a central and two side openings for the reception of vessels, dampers in the respective conduits, a rod extending transversely through all the conduits and having the dampers in the side conduits fixed thereon, and means providing a lost connection between said rod and the damper in the central conduit, and means normally holding the last named damper in open position. 125

In testimony whereof I have affixed my signature.

MARIANO LA BARBERA.
